REVERSING SWITCH

William A. Bowling, Charleston, W. Va.

Application May 20, 1942, Serial No. 443,789

3 Claims. (Cl. 200—1)

The invention relates to improvements in reversing switches for three-phase alternating current motors, and the primary object of the invention is to provide a simplified, reliable, reversing switch of this type which can be made in various sizes and current ratings, notwithstanding a relatively small over all bulk.

Other important objects and advantages of the invention will be apparent from a reading of the following description taken in connection with the appended drawings, wherein for purposes of illustration a preferred embodiment of the invention is shown.

In the drawings:

Figure 1 is an end elevational view of the embodiment.

Figure 2 is a front elevational view.

Figure 3 is an enlarged top plan view.

Figure 4 is a perspective view of one of the stationary contacts.

Figure 5 is a schematic diagram illustrating connection of the switch between a line switch and a three-phase alternating current motor starter and the motor, showing the reversing switch installed in the motor starter and with the reversing switch in the up-position.

Figure 6 is a view similar to Figure 5 but showing the reversing switch in down-position.

Figure 7 is a schematic wiring diagram showing utilization of the reversing switch of the invention for reversing a direct current motor by reversing the fields thereof.

Figure 8 is a schematic wiring diagram showing utilization of the present reversing switch to reverse the charge into a storage battery on a battery charging panel.

Figure 9 is a schematic wiring diagram illustrating application of the present reversing switch to a split-phase type of single-phase motor.

Referring in detail to the drawings, the numeral 5 generally designates the reversing switch as a whole which comprises a generally rectangular dielectric material or otherwise suitably insulated base 6. On the top of the base are mounted the four similar contacts 7, 8, 9, and 10, respectively. Each contact consists of a horizontal plate 11 having a depending lug 12 to engage the outer end of the base 6 with the portion 11 lying on the top of the base and secured by means of a binding post 13 passing through a hole 14 in the portion 11. The end of the plate portion 11 is beveled or concaved as indicated by the numeral 15.

An insulated hollow cylinder 16 of approximately the same dimension in length as the 55

width of the base 6 has countersunk in its surface at each end thereof the contact segments 17 which are of sufficient circumferential dimension to more than bridge the space between the beveled ends 15 of the opposed contacts 7, 9 and 8, 10 on the opposite sides of the base 6, in the manner indicated in Figure 1 of the drawings when the cylinder 16 is in the position shown in Figure 1. In a diametrically opposite position from the contactors 17 are the pairs of circumferentially spaced contactor segments 18, 19 and 20, 21 at the opposite ends of the cylinder 16. Wires 22 and 23 connect the contactor segments 19 and 20, and 18 and 21, respectively, as indicated in dotted lines in Figure 3 of the drawings, the wires being insulated from each other.

Holding the drum 16 assembled to the base 6 and frictionally resisting rotation of the drum 16 is a spring band 24 which has one end anchored 20 as indicated by the numeral 25 to the front end of the base 6 and has its opposite end provided with an opening receiving the hook 26 on the contractile spring 27 whose lower end is anchored to the rear end of the base as indicated by the numeral 28.

Studs 29 and 30, anchored in one side of the cylinder 16 between the contactors 17 and the pairs of contactor segments 21 projects radially from the end portions of the cylinder and connect at their outer ends with a handle piece 31 which has an insulating material handle 32 thereon, the handle being adapted to be grasped manually to turn the cylinder 16 from the downward position illustrated in Figure 1 of the drawings to the up-position in which the pairs of contactor segments 13 and 19 and 20 and 21 engage the contacts 7, 9 and 8, 10, instead of these contacts being engaged by the contactor segments 17. By this change in position of the cylinder 16 the current flows between the contacts 7 and 10 and 8 and 9, respectively, instead of through the contacts 7, 9 and 8, 10 in the position shown in full lines in Figure 1 of the drawings, thereby reversing the direction of the current.

Referring to Figures 5 and 6 of the drawings the numeral 35 symbolically designates a conventional form of motor starter in which the reversing switch of the present invention can advantageously be incorporated, with the wires 36 and 37, for instance, leading through the contacts 7, 9, and 8, 10, respectively, of the reversing switch 5 to the motor M, with the reversing switch in the down-position. In the up-position of the handle 32 of the reversing switch 5, illustrated in Figure 6 of the drawings, the current

is reversed to the motor M by the consequent flow of the current through the wire 36 from the contact 7 to the contact 10 and in the wire 37 from the contact 8 to the contact 9, instead of to the contacts of the reversing switch in the first described arrangement, whereby the operation of the motor M is reversed.

Referring to Figure 7 of the drawings showing an employment of the reversing switch of the invention for reversing a direct current motor having the armature A and the shunt field coil F, one side of the shunt field may be connected to the contact 10 of the remaining side of the field to the contact 9. The contacts 7 and 8 may be connected to opposite sides of the armature winding A and at points between the corresponding sides of the armature winding and the two lines 38 and 39 of the D. C. current supply. In this instance, changing the position of the cylinder 16 by operation of the handle 32 in the manner already described accomplishes reversal of the D. C. motor.

Referring now to Figure 8 of the drawings illustrating employment of the present reversing switch in storage battery charging panel, the letter B generally designates the storage battery which is connected with one side on the contact 9 and the other side on the contact 10, with the contacts 7 and 8 of the reversing switch connected to corresponding sides of the current supply as indicated, reversal of the charging current through the battery B being accomplished by operation of the cylinder 16 of the reversing switch in the manner already described.

Figure 9 of the drawings shows connection of the reversing switch 5 to reverse a split-phase type of single phase (A. C.) motor 39 having a centrifugal switch 40 to open the starting winding 41, with the opposite sides of the starting winding connected to the switch contacts 7 and 8. The contacts 9 and 10 of the reversing switch are connected to the opposite sides of the main winding 42 and to the supply current input wires 43 and 44, respectively, with a single pole hand switch 45 connected in the wire 44.

Although there are shown and described herein preferred embodiments of the invention, it is to be definitely understood that it is not desired to limit the application of the invention thereto, except as may be required by the scope of the subjoined claims.

Having described the invention, what is claimed as new is:

1. A reversing switch comprising an insulated base, a first pair of laterally spaced stationary contacts on said base, a second pair of laterally spaced stationary contacts on said base, said pairs of stationary contacts being longitudinally spaced from each other and exposed at the top of said base, an insulated cylinder lying across said top of the base between said pairs of contacts, a handle on said cylinder for rotating the cylinder on said base, spring pressed friction means assembling said cylinder on said base and resisting rotation of said cylinder on its axis, single contactor segments on one side of said cylinder, said single contactor segments being

5 axially spaced from each other and positioned to bridge the transversely aligned stationary contacts, two pairs of dual contact segments on the diametrically opposite side of said cylinder at the opposite ends of said cylinder, crossed and insulated conductors connecting the diagonally related contacts of the last mentioned pairs, said wires passing through the cylinder, said dual contact segments being arranged to severally engage

10 the transversely aligned stationary contacts when the cylinder is rotated substantially a half revolution from the position in which the single contactor segments engage the transversely aligned stationary contacts.

15 2. A reversing switch comprising an insulated base, a first pair of laterally spaced stationary contacts on said base, a second pair of laterally spaced stationary contacts on said base, said pairs of stationary contacts being longitudinally spaced 20 from each other and exposed at the top of said base, an insulated cylinder lying across said top of said base between said pairs of contacts, a handle on said cylinder for rotating the cylinder on said base, spring pressed friction means assembling 25 said cylinder on said base and resisting rotation of said cylinder on its axis, single contactor segments on one side of said cylinder, said single contactor segments being axially spaced from each other and positioned to bridge the trans-

30 versely aligned stationary contacts, two pairs of dual contact segments on the diametrically opposite side of said cylinder at the opposite end of said cylinder, crossed and insulated conductors connected the diagonally related contacts of the

35 last mentioned pairs, said wires passing through the cylinder, said dual contact segments being arranged to severally engage the transversely aligned stationary contacts when the cylinder is rotated substantially a half revolution from the

40 position in which the single contactor segments engage the transversely aligned stationary contacts, binding posts assembling said stationary contacts on said base, said contacts comprising plates lying on the top of said base with their

45 adjacent ends beveled to conformably engage the curved surface of said cylinder and the contactor segments thereon.

3. A reversing switch comprising an axially rotatable insulated cylinder, a longitudinally spaced and aligned pair of single contactor segments on one side of said cylinder, two pairs of longitudinally spaced and aligned dual contactor segments on the opposite side of said cylinder, the dual contactor segments being insulated from

55 each other, means for rotating said cylinder, an insulated base having two pairs of stationary contacts thereon, the contacts of each pair being laterally spaced to align with the longitudinally spaced segments on the cylinder, said single segments being arranged to bridge adjacent contacts

60 in one position of rotation of the cylinder and said dual segments being arranged to severally engage the contacts in another position of rotation of the cylinder, crossed insulated conductors

65 diagonally connecting said dual contactors, and means assembling said cylinder on said base.

WILLIAM A. BOWLING.
